E. D. MORGAN

VEHICLE TOP CONSTRUCTION

Filed Jan. 5, 1922

Inventor:
Earl D. Morgan,
By James T. Barker,
his attorney.

UNITED STATES PATENT OFFICE.

EARL D. MORGAN, OF LOS ANGELES, CALIFORNIA, ASSIGNOR OF ONE-HALF TO
HENRY B. DAY, OF LOS ANGELES, CALIFORNIA.

VEHICLE-TOP CONSTRUCTION.

Application filed January 5, 1922. Serial No. 527,074.

To all whom it may concern:

Be it known that I, EARL D. MORGAN, a citizen of the United States, residing at Los Angeles, in the county of Los Angeles and 5 State of California, have invented new and useful Improvements in Vehicle-Top Constructions, of which the following is a full, clear, and accurate disclosure.

While my invention pertains generally to 10 a vehicle top construction, it pertains more particularly to a type of top construction—commonly termed "all weather"—wherein movable or adjustable side windows are so hung and constructed that a top of the touring car type may be very easily and readily 15 converted into a top of the limousine type, merely by proper adjustment of these windows.

The foremost characteristics of my invention 20 reside in the arrangement, hanging and fittings of these sliding windows, to readily accomplish the aforementioned purpose; and in the provision of simple and efficient means for holding the said windows in different or adjusted positions, and against rattling when the vehicle is in motion.

The salient features of the invention will 25 be more clearly set forth in the following specification, reference being made therein 30 to the accompanying drawings, in which it is illustrated, and in which:

Fig. 1 is a longitudinal vertical section, taken through the center of a typical motor vehicle body and top, showing my invention 35 as applied thereto; Fig. 2 is an enlarged fragmentary transverse detail section taken as indicated by the line 2—2 on Fig. 1; Fig. 3 is a fragmentary longitudinal section taken as indicated by the line 3—3 of Fig. 2; Fig. 40 4 is an enlarged fragmentary side elevation of a portion of the structure, being taken as indicated by the line 4—4 of Fig. 2; and Fig. 5 is an enlarged transverse vertical section similar to that shown in Fig. 45 2, and taken as indicated by the line 5—5 of Fig. 4.

In keeping with the rapid advance and the growth and development of the motor vehicle industry, a top for the vehicle body 50 has been recently developed which is substantially a combination of the old type of collapsible or folding top for touring cars and the permanent top structures of limousines, and the like. That is, it is an open

sided top constructed along the general lines 55 of the first mentioned touring car type, but is of a permanent character and cannot be collapsed or folded, as those of the previous types; and it is in connection with this type of top that my invention will have its widest 60 application.

Referring now to the drawings, and particularly to Fig. 1, the numeral 10 designates generally the vehicle body, containing the front and rear seats 12 and 13, and front 65 and rear doors 14 and 15, respectively; the latter for gaining access to the former in the usual manner.

A top, of the permanent type of structure above mentioned, is generally designated by 70 the numeral 16; this being mounted on the top of the vehicle body, and supported by a back or rear wall 17, on the rear 18 of the vehicle body, and by a front windshield structure 19. The top 16 is further supported, and the rear seat 13 enclosed at its ends, by side wall structures 20, in the manner illustrated in Fig. 1. The side walls 20 preferably are integral with and extend from the back 17 to a point at or just to 80 the rear of the rear side of the doors 15.

The top 16 may be of any suitable type of structure desired, as far as the bracing and supporting members are concerned; it being only necessary to provide ample structure to 85 properly carry an outer covering 21 and, if desired, an inner finish or lining 22, as herein illustrated. This may consist of suitable bows 23 and longitudinal slats or ribs 24 for carrying the fabrics 21 and 22.

It is essential, however, that inner and outer longitudinal rails 25 and 26, respectively, be provided for supporting or carrying the inner and outer, or front and middle, closure windows 27 and 28, respectively, 90 which are provided for suitably enclosing the top 16, in the manner hereinafter described.

The rear side walls 20 consist of inner and outer wall structures 20^a and 20^b, spaced 95 slightly apart to receive the windows 27 and 28 when they are in their rearward positions, as indicated by dotted lines in Fig. 1; these wall structures being provided with glass inserts or windows 29, if desired, to add to the effectiveness of the top. The longitudinal rails 25 and 26 are supported at the their rear ends upon these walls 20^a

and 20^b, and at their front ends are joined to a transverse member 30, and the whole forward end of the top supported upon the windshield structure 19.

5 The longitudinal rails 25 and 26 are preferably of the cross sectional configuration shown in Fig. 2; that is, angular or L-shaped, and positioned so that their angular recess or rabbeted corners oppose each 10 other; and being held in their spaced relation by a longitudinal spacing and bracing member 30. This spacer member 30 is rigidly secured between the vertical arms 31 of the rails 25 and 26; while the lower 15 or horizontal arms 32 extend towards each other and carry tracks 33 and 34, upon which the windows 27 and 28 are slidably mounted. The tracks 33 and 34 are preferably constructed of a suitable metal, such as 20 strap-iron; and may be secured to the contiguous faces of the horizontal arms 32 by means of screws or the like; the arms 32 being rabbeted as at 35 to receive them. The rails 25 and 26, together with the tracks 33 25 and 34, extend from the front end of the top 16, or the transverse member 30, to a point adjacent the rear wall 17, in order that either of the windows 27 or 28 (both of which are suspended between them) may 30 be moved the entire length of the top as desired.

The windows 27 and 28 are identical and consist of the usual frames 36 supporting panels 37 of glass or a suitable transparent 35 or translucent material. Hangers 38 are secured to the faces of the frames 36 at their upper edges, by means of screws 39; the faces of these frames being recessed to receive these hangers, as shown in Fig. 2. 40 The upper ends of these hangers are offset, or set out relative to the vertical faces of the sash, and are curved, as at 40, forming inverted U-shaped hooks to engage and slide upon the top edges of the tracks 33 and 34. 45 Each of the windows 27 and 28 is provided with two of the hangers 38; they being secured to the upper members of frames 36 adjacent their ends, and close to the vertical members of the frames, as clearly shown in 50 Figs. 1 and 3. The windows 27 and 28 are of such height, that when they are supported upon or suspended from the tracks 33 and 34 by the hangers 38, as above described, the bottom faces 41 of the frames, (see 55 Figs. 2, 4 and 5) will be spaced slightly from the top faces 42 of the doors 14 and 15, and of the sides of the vehicle body. This permits the windows to be very easily 60 and freely moved by hand, to and from their several positions, to either close or open the sides of the top.

Channel members 43 are secured to the bottom faces 41 of frame 36 (see Figs. 2, 4 and 5) with their webs 44 in contact with 65 the faces 41 and their flanges 45 extending

downwardly to a point spaced only slightly from the top faces 42 of the vehicle body and doors. Blocks of leather 46, or a similar more or less yielding material, are secured to the top faces 42 of the vehicle body 10, 70 as by means of screws 47; being of any desired length and so spaced along the top of the vehicle body that they will be engaged by the channel members 43 on the bottoms of the windows 27 and 28, at points 75 near the ends of the channels, when these windows are either in their open position, or in their closed positions, forward thereof, as shown in Fig. 1. These blocks are shown in dotted lines in Fig. 1 to indicate 80 their positions.

The blocks 46 may be of any length, as above stated, but they need not be more than a few inches long; and in cross sections they are of such size as to extend part way 85 into the channels 43^a of the channel members 43, so their upper corners 46^a will contact with the inclined inner faces 45^a of the flanges 45. This engagement between the inner inclined faces 45^a and the corners 46^a 90 will be substantially the only contact between the blocks 46 and the channel members 43. While it may be preferable to have the blocks 46 cut in short lengths, as hereinbefore described, they may also form continuous strips along the tops of the doors 14 and 15 of the vehicle body, if desired, without departing from the spirit of the invention. 95

From the foregoing disclosure it is readily apparent that this manner of supporting and hanging the windows 27 and 28 will permit them to be very easily and conveniently moved from their rearward or open positions, between the walls 20^a and 20^b, to 100 their forward positions over the doors 14 and 15 (as shown in Fig. 1). It is also clear that they may be moved to either enclose just the tonneau, or the front seat alone, or both of them. 110

In order that either or both of the windows 27 and 28 may be held in any of the foregoing described positions, to entirely or partially enclose the seats of the vehicle, or either of them; and to also hold them against rattling when in any of these positions, I have provided the following described mechanism. 115

A plurality of shafts 50 are revolvably journaled in suitable bearings 51, in the vertical arms 31, of the longitudinal rails 25 and 26, so as to extend transversely of them and in a horizontal position above the frames 36 of the windows 27 and 28. 120 Any number of these may be provided, but in the interests of economy and simplicity I provide only three, each disposed in a position to be substantially in the transverse centers of the windows when in either their open or closed positions. This arrangement 125 130

is clearly illustrated in dotted lines in Fig. 1. Each of the shafts 50 has a cam member 52 rigidly mounted thereon, it preferably being circular and mounted eccentric 5 of the shaft, (see Fig. 3) and of a width to extend substantially across and to engage the upper edges of both of the frames 36 of the windows 27 and 28, when beneath them. These cam members 52 are so mounted 10 upon the shaft 50, intermediate the spacer member 30 and the top faces of the frames 36, so that rotation of the shafts 50 will cause the cams to engage or disengage these top faces, and thereby force the windows 27 15 and 28 downwardly so the spike of the hook 40, of the hangers 38, will tightly engage the tracks 33 and 34; while the flanges 45, of the channel members 43, will at the same time tightly engage the leather block 46, 20 as hereinbefore specified.

Each of the shafts 50 carries a crank arm 53, rigidly mounted thereon, so as to extend upwardly (see Figs. 1 and 2) each of these crank arms being connected by a 25 rod 54, so that rotation of one of the shafts 50 will cause rotation of the other simultaneously.

The shafts 50, adjacent the front seat 12, extend outwardly through an opening 30 55, in the top lining 22, and an operating lever 56 is rigidly secured thereto; the latter having a handle 57 for the purpose of rotating the shafts 50 and causing engagement or disengagement of the cam members 52 with the top faces of the frames 36, of the windows 27 and 28, as hereinbefore described.

A stop member 57 is rigidly secured to the spacer member 30, or any other convenient place, to extend across the plane of movement of the forward crank arm 53, so as to limit the movement of this member in one direction; and, through the medium of the connecting rod 54, likewise simultaneously limit the movement of the other crank arm. This stop member 57 is so positioned to stop rotation of the shafts 50, and consequently the cam members 52, when the latter have reached the positions shown 45 in Fig. 3. From this it is clear that movement of the operating lever 56 in the direction indicated by the arrows, in Figs. 1 and 3, will cause rotation of the cam members 52 from the position shown in full 50 lines in Fig. 3, to that shown in dot-dash lines in that figure, thereby causing their disengagement with the top face of the frames 36. This will relieve their clamping effect and permit the windows 27 and 55 28 to be moved as desired. When the cam members 52 are in the position shown in full lines in Fig. 3, the windows 27 and 28 are held downwardly and the hangers 38 in engagement with the tracks 33 and 34, 60 and the channel members 43 in engagement

with the block 46, to hold them against further movement, and also against rattling.

The cam members 52 are so mounted upon the shafts 50 that when the crank arm 53 is in engagement with the stop member 57, 70 their high point will have passed beyond the vertical centers of the shafts and windows and will be held in such position by the yielding or resilient action of the frames 36. This will tend to lock the cam members 75 in this position, and they can only be removed therefrom by movement of the operating lever 56 in the direction indicated by the arrow.

I have purposely arranged to mount the 80 cam members in position so that by operation of the shafts 50 the former will engage the frames of the windows intermediate of, or substantially central of their hangers 38. This, owing to a certain resilient or yielding quality of the top members of frames 36, and the longitudinal rails 25 and 26, which are all lightly constructed, will permit a slight spreading of these members, as indicated by the arrows and 85 letter A in Fig. 3, when the cam members are moved to the position shown in solid lines in that figure, which will tend to hold the cam member in this position past its 90 dead center.

While I have here shown and described the preferred embodiment of my invention, it is nevertheless to be understood that I reserve the right to make any changes or modifications in structure which will properly come within the scope of the appended 95 claims.

Having described a preferred embodiment of my invention, I claim:

1. In a vehicle top construction of the 100 class described, the combination of a plurality of parallel supporting rails above and parallel to the side of the vehicle body, longitudinally sliding hangers on each rail, panels carried by the hangers, the several 110 panels being slideable past each other on their rails, and a cam mounted on a transverse axis above the several panels and of sufficient extent parallel to its axis to lie above the paths of all the several panels and adapted by rotation to bear down on the upper edges of all the panels to hold their hangers down in frictional engagement with their rails.

2. In a vehicle top construction of the 115 class described, the combination of a plurality of parallel rails, longitudinally sliding hangers on each rail, panels carried by the hangers the several panels being slideable past each other on their rails, a plurality of cams spaced along the rails each cam mounted on a transverse axis above the several panels and of sufficient extent parallel to its axis to lie above the paths 120 of all the several panels and adapted by 125

rotation to bear down on the upper edges of all the panels to hold their hangers in frictional engagement with their rails, and a single operating means for the several cams.

3. In a vehicle top construction of the class described, in combination with a vehicle body, a top structure embodying an outer top wall and an inner top wall spaced apart in a horizontal transverse direction at the edges of the top structure, a pair of parallel rails extending along the spaced edges of the two spaced top structure walls, longitudinally sliding hangers on each rail, panels carried and means located in the space between the two spaced walls of the top structure and adapted to bear down on the several panels to hold their hangers in frictional engagement with their rails, said means embodying a plurality of cams spaced along the rails, each cam mounted on an axis transverse of the rails and each cam having a sufficient extent parallel to its axis to lie above the paths of the several panels, and means to rotate said cams to

bring them to bear downwardly on the several panels.

4. In a vehicle top construction of the class described, the combination of a pair of parallel supporting rails, a pair of sash members each independently movably mounted on one of said rails, said mountings consisting each of a pair of hangers secured adjacent either end of said sash members, inverted channel members carried on the bottoms of said sash members, guide members mounted on the top of side of the vehicle body and adapted to extend into said channel members, and a plurality of clamping members in the form of cams carried by said supporting rails and adapted to engage the top rails of one or both of said sash members intermediate said hangers to clamp said hangers in engagement with said rails and said channel members in engagement with said guide members.

In witness that I claim the foregoing I have hereunto subscribed my name this 24th day of December, 1921.

EARL D. MORGAN.
